(57) **CLAIM**

The ornamental design for a protective cover for flat screen television, as shown and described.

DESCRIPTION

FIG. 1 is a front elevation view of a protective cover for flat screen television showing my new design;
FIG. 2 is a rear elevation view thereof;
FIG. 3 is a top plan view thereof;
FIG. 4 is a bottom plan view thereof;
FIG. 5 is a right elevation view thereof, the opposite side being a mirror image thereof; and,
FIG. 6 is an isometric view thereof.
The broken lines in FIG. 6 depict environmental subject matter only and form no part of the claimed design.
